Inventor:
Harry C. Johansen.
by *H. C. Johansen*
Attorney.

UNITED STATES PATENT OFFICE

HARRY C. JOHANSEN, OF MICHIGAN CITY, INDIANA, ASSIGNOR TO SULLIVAN MACHINERY COMPANY, A CORPORATION OF MASSACHUSETTS

CORE DRILL

Application filed October 21, 1924. Serial No. 746,959.

My invention relates to core drills.

An object of my invention is to provide an improved core barrel for such a drill. Another object of my invention is to provide an improved combined single and double tube core barrel. Still another object of my invention is to provide an improved core barrel of the combined single and double tube type especially adapted for oil well drilling 10 wherein but a single tube may be used when hard drilling is encountered and a double tube may be used when soft drilling is encountered. A still further object of my invention is to provide an improved double 15 tube core barrel wherein the inner tube is arranged within the outer tube in an improved manner. These and other objects and advantages of my invention will hereinafter more fully appear.

20 In the accompanying drawings I have shown for purposes of illustration one form which my invention may assume in practice.

In these drawings,—

25 Fig. 1 is a longitudinal sectional view through my improved core barrel, the view being taken substantially on line 1—1 of Fig. 2.

Fig. 2 is an end elevation of the cutting end of my improved core barrel.

30 Fig. 3 is a transverse horizontal sectional view taken substantially on line 3—3 of Fig. 1.

Fig. 4 is a transverse horizontal sectional view taken substantially on line 4—4 of Fig. 1.

Fig. 5 is a view similar to that shown in Fig. 1, with the inner core barrel removed.

Fig. 6 is an elevation view of the inner core barrel.

40 In this illustrative form of my invention I have shown a core barrel generally designated 1 which threadedly engages threads 2 formed on the usual hollow drill rod 3. The core barrel 1 comprises a head member 4 provided with threads 5 which engage the threads 2 formed on the lower end of the drill rod and this head member is secured as by welding to the outer tube 6 of the barrel. The tube 6 threadedly engages as at 7 a core lock casing 8 which is in turn threaded as

at 9 to a drill bit 10, the latter being of the usual rotary diamond type. The drill bit 10 is provided with an internal conical bore 11 in which the usual resilient split core lifter 12 is disposed. The core lock casing 8 is 55 provided with a bore 13 which is eccentrically bored as at 14 to form a ledge 15.

Water or mud fluid is adapted to be delivered to the cutting edge of the drill bit 10 through the hollow drill rods 3 from any 60 suitable source and into a bore or chamber 16 formed within the head member 4. The lower end of the bore 16 is provided with a reduced central opening 17 which communicates with the interior of the outer tube 6 and the water or mud fluid passes downwardly through this opening, through the other tube of the core barrel, and through a series of openings 18 and 19 formed in the core lock 8 and the drill bit 10, respectively. 70 The periphery of the drill bit 10 is fluted as at 20 to permit the flow of fluid along the exterior of the core barrel and upwardly from the hole in the usual manner.

75 In my improved construction it will be observed that the lower end of the head member 4 is provided on its lower surface adjacent the opening 17 with radially spaced teeth 21 which interlock with teeth 22 formed on the upper surface of a plug member 23. The 80 plug member 23 threadedly engages, as at 24, the upper end of an inner core receiving tube 25 which is provided at its lower end with a cylindrical portion 26 of reduced diameter adapted to freely fit in a bore 27 formed in 85 the upper part of the core lock casing 8. The plug 23 is provided with projections 28 on its outer surface which are adapted to guide the upper end of the inner tube 25 within the outer tube 26. The interior of the inner tube 25 is vented by means of a small port 29 formed within the plug member 23.

90 In the use of my improved core barrel it will be noted that during soft drilling the drill bit 10, which is rotated in any suitable 95 manner, cuts out a core of the material being drilled and this core passes through the core lifter 12 and the core lock casing 8 into the inner tube 25 of the core barrel which is held in non-rotative relation by means of the 100

clutch teeth 21, 22. The water or mud fluid then passes from the hollow drill rods 3 into the chamber 16 within the head member 4 through the opening 17 and downwardly 5 around the exterior of the inner tube 25 and through the openings 18, 19 in the core lock casing 8 and the drill bit 10, respectively, to wash away the cuttings and to seal the hole. Fluid is consequently prevented from washing 10 over the soft core and the core barrel at that time being used as a double tube barrel. When it is desired to remove the core from the hole, the core barrel is raised upwardly, by any suitable means, consequently causing 15 the core lifter 12 to grip the core and break the latter off. The ledge 15 formed within the core lock casing 8 prevents the core from moving downwardly within the core barrel in case that the core lifter 12 does not rigidly 20 grip the core. When hard drilling is encountered the core barrel is removed from the hole and the core lock casing 8 unthreaded from the lower end of the outer tube 6 permitting the inner tube 25 to be bodily removed longitudinally 25 from the barrel and the core barrel thereafter being used as the single tube barrel. When the core barrel is used in this manner, the mud fluid passes from the drill rods 3 into the chamber 16 through the opening 17 30 and through the interior of the tube 6 around the exterior of the relatively hard core and through the openings 18 and 19 to the cutting edge of the bit.

As a result of my improvement it will herein be noted that I have provided an improved core barrel of the combined single and double tube type especially adapted to use in oil well drilling and which may be utilized in either hard or soft drilling, consequently eliminating 35 the necessity of two separate barrels and decreasing the cost of the device.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a core drill, an outer core barrel and a bit carried at the inner end thereof, a detachable inner core barrel, a detachable core lock casing secured to said outer barrel and in which said inner barrel is seated, core lifting means carried by said core lock casing, and a sliding interlocking connection between said barrels for preventing relative rotation therebetween.

2. In a core drill, an outer core barrel and a bit carried at the inner end thereof, a detachable inner core barrel, a detachable core lock casing secured to said outer barrel and in which said inner barrel is seated, core lift-

ing means carried by said core lock casing, and a sliding interlocking connection between said barrels for preventing relative rotation therebetween, said interlocking connection being releasable purely by straight 70 longitudinal movement of said inner barrel relative to said outer barrel upon removal of said core lock casing from the latter.

3. In a core drill, an outer core barrel, an inner core barrel, a core lock casing detachably secured to said outer barrel and in which said inner barrel is seated and supported, said inner barrel being freely longitudinally movable from said outer barrel upon removal of said core lock casing from said outer barrel, core lifting means carried by said core lock casing, a bit detachably secured to said core lock casing having a core receiving passage, and means for conducting fluid from between said barrels through said core lock 80 casing and through said bit externally of the core passage therein to the bottom of the hole.

4. In a core drill, an outer core barrel, an inner core barrel, a core lock casing secured to said outer barrel and in which the lower 90 end of said inner barrel is seated and supported, core lifting means carried by said core lock casing, a sliding interlocking connection between the upper ends of said barrels for preventing relative rotation therebetween, a bit detachably secured to said core lock casing and having a core receiving passage, and means for conducting fluid from between said barrels through said core lock 95 casing and through said bit externally of said core passage to the bottom of the hole.

5. In a core drill, an outer core barrel, an inner core barrel having a core receiving chamber, a core lock casing secured to said outer barrel and in which said inner barrel is seated and supported, said inner barrel being freely longitudinally movable from said outer barrel upon removal of said core lock casing from said outer barrel, said casing having a core receiving passage, core lifting means carried by said core lock casing, a bit detachably secured to said core lock casing and having a core receiving passage, and means for conducting fluid from between said barrels through said core lock 110 casing and through said bit externally of the core receiving passage.

6. In a core drill, an outer core barrel, an inner core barrel, a core lock casing secured to said outer barrel and in which said inner barrel is seated, a bit secured to said casing, a core lifter carried by said bit, and supplemental core engaging means carried by said core lock casing.

7. In a core drill, a combined single and double tube core barrel comprising concentric tubes adapted to selectively receive a core, and a core lock casing, core lifting means carried by said core lock casing, means for slidably interlocking the upper 125

ends of said tubes for preventing relative rotation therebetween, means to seat and support the inner one of said tubes in the upper end of said core lock casing, and a bit detachably secured to said core lock casing.

8. In a core drill, an outer core barrel and a bit carried at the inner end thereof, a detachable inner core barrel, said inner barrel being provided with a closure plug at the upper end thereof, a core lock casing secured to said outer barrel and in which said inner barrel is seated and supported, core lifting means carried by said core lock casing, and means for slidably interlocking said barrels together to prevent relative rotation therebetween including positive locking means carried by said plug.

9. In a core drill, an outer core barrel and a bit carried at the inner end thereof, a detachable inner core barrel having a core receiving chamber, said inner barrel being provided with a closure plug at the upper end thereof, a core lock casing secured to said outer barrel and in which said inner barrel is seated and supported, core lifting means carried by said core lock casing, means for positively slidably interlocking said barrels together to prevent relative rotation therebetween including locking means carried by said plug, and vent means for said core receiving chamber.

10. In a core drill, an outer core barrel, an inner core barrel, a sliding interlocking connection between said barrels to prevent relative rotation therebetween, a core lock casing carried by said outer barrel and in which said inner barrel is seated and supported, core lifting means carried by said core lock casing, a bit carried by said casing, and means for guiding the upper end of said inner barrel for maintaining said inner barrel in substantial alignment with said outer barrel during insertion of the former barrel within the latter.

45 11. In a core drill, a combined single and double tube core barrel comprising concentric inner and outer tubes, a core lock casing detachably secured to the outer tube, core lifting means carried by said core lock casing, means for seating the inner one of said tubes in said core lock casing, a bit detachably secured to said core lock casing, said core lock casing forming a coupling between said outer tube and said bit, and supplemental core lifting means carried by said bit.

12. In a core drill, a combined single and double tube core barrel comprising concentric inner and outer tubes adapted to selectively receive a core, a core lock casing detachably secured to the outer tube, core lifting means carried by said core lock casing, means for interlocking the upper ends of said tubes to prevent relative rotation therebetween, means to seat the inner one of said

tubes in the upper end of said core lock casing, a bit detachably secured to said core lock casing, said core lock casing forming a coupling between said outer barrel and said bit, and supplemental core lifting means carried by said bit.

13. In a core drill, an outer core barrel, a detachable inner core barrel, a core lock casing detachably secured to said outer barrel and in which said inner barrel is seated, core lifting means carried by said core lock casing, a sliding interlocking connection between said barrels for preventing relative rotation therebetween, a bit detachably secured to said core lock casing, said core lock casing forming a coupling between said outer tube and said bit, and supplemental core lifting means carried by said bit.

14. In a core drill, an outer core barrel, an inner core barrel, a core lock casing secured to said outer barrel and in which said inner barrel is seated, a sliding interlocking connection between the upper ends of said barrels for preventing relative rotation therebetween, a bit secured to said core lock casing, a core lifter carried by said bit, and supplemental core engaging means carried by said core lock casing.

15. In a core drill, an outer barrel and a bit carried at the inner end thereof, a detachable inner core barrel, detachable means secured to the lower end of said outer barrel and in which the lower end of said inner barrel is seated and supported, and a sliding interlocking connection between the upper ends of said barrels for preventing relative rotation therebetween, said inner barrel being releasable from said outer barrel by straight longitudinal movement relative thereto after said seating means has been detached from said outer barrel.

16. In a core drill, an outer barrel and a bit carried at the inner end thereof, a detachable inner core barrel, detachable means secured to the lower end of said outer barrel and in which the lower end of said inner barrel is seated and supported, and means for locking the upper ends of said barrels together to prevent rotation of said inner barrel relative to said outer barrel, said locking means being releasable by straight longitudinal movement of said inner barrel relative to said outer barrel after said seating means has been detached from said outer barrel.

17. In a core drill, an outer core barrel and a bit carried at the inner end thereof, a detachable inner core barrel, detachable means secured to the lower end of said outer barrel and in which the lower end of said inner barrel is seated and supported, and locking means comprising clutch teeth carried by the upper ends of said barrels respectively for locking the same together to prevent rotation of said inner barrel relative to

said outer barrel, said locking means being releasable by straight longitudinal movement of said inner barrel relative to said outer barrel after said seating means has 5 been detached from said outer barrel.

In testimony whereof I affix my signature.

HARRY C. JOHANSEN.
